UNITED STATES PATENT OFFICE.

ARTHUR W. LAMP, OF CLEVELAND, OHIO, ASSIGNOR TO WALTER J. CARTER, OF CLEVELAND, OHIO.

PROCESS OF MAKING BRUSHES.

1,415,657.

Specification of Letters Patent.

Patented May 9, 1922.

Application filed August 13, 1920. Serial No. 403,253.

To all whom it may concern:

Be it known that I, ARTHUR W. LAMP, a citizen of the United States, residing at Cleveland, in the county of Cuyahoga and 5 State of Ohio, have invented a certain new and useful Improvement in Processes of Making Brushes, of which the following is a full, clear, and exact description, reference being had to the accompanying drawings.

This invention relates to brushes of the type wherein tufts of brush material (preferably wire) are looped about pins or posts supported by opposed heads. The object of 15 the invention is to provide a process for making such brushes which will enable the latter to be manufactured with great rapidity and economy of production. In making brushes in accordance with my invention, 20 it is possible to employ for the same, simple and easily formed brush elements which are inexpensive of manufacture.

In the accompanying drawing wherein I have shown an illustrative embodiment of 25 my invention, Fig. 1 is a vertical sectional view of the brush head showing the brush material supporting elements in position; Fig. 2 is a similar view showing the extension pins in position and the brush material 30 assembled thereon; Fig. 3 a vertical sectional view showing the method of compressing and clamping the brush material in the brush head; Fig. 4 is an elevation of the completed article; Fig. 5 is a plan view with 35 parts broken away to show the manner in which the brush material is disposed about the supporting elements; Fig. 6 is a similar view of a modification wherein the brush material is alternated about the circumference of the head; Fig. 7 is a sectional view 40 taken on the line 7—7 of Fig. 6 and Figs. 8 and 9 are perspective and vertical sectional views respectively of modifications of the brush material supporting elements.

45 Describing by reference characters, the various parts and steps illustrated, 1 indicates an annular side head which is provided adjacent the circumferential edge thereof with a series of countersunk apertures 2, each of 50 which receives a brush-material supporting element 3. The elements 3 will be designated as posts hereinafter and may be formed from seamless tubing as shown in Fig. 1, or from seamed tubing as shown in 55 Fig. 8, or from a rod as shown in Fig. 9, the

latter being provided at one end with a bore 5, the purpose of which will become apparent as the description proceeds. Each post is formed at one end with a headed portion 6 which in the case of the tubing is formed by 60 flaring one end thereof, and in the case of the rod by upsetting an end or by turning down the body portion thereof. The headed portions so formed are adapted to fit within the countersunk portions of the apertures 65 2 and to lie flush with the outer surface of the head 1. An extension or guide pin 9, having a reduced portion 10 and a tapered shoulder 11, is next inserted into each of the posts 3, thus permitting a series of brush 70 material tufts 12 of greater aggregate width than the finished brush to be looped about the posts and their respective extensions, as shown in Fig. 2. After a sufficient number of tufts have been applied to permit forming a brush of the desired width when compressed, a head 14, similar in shape to the head 1 is fitted over the extension pins. 75 In the accompanying drawing wherein I have shown an illustrative embodiment of my invention, Fig. 1 is a vertical sectional view of the brush head showing the brush material supporting elements in position; Fig. 2 is a similar view showing the extension pins in position and the brush material assembled thereon; Fig. 3 a vertical sectional view showing the method of compressing and clamping the brush material in the brush head; Fig. 4 is an elevation of the completed article; Fig. 5 is a plan view with parts broken away to show the manner in which the brush material is disposed about the supporting elements; Fig. 6 is a similar view of a modification wherein the brush material is alternated about the circumference of the head; Fig. 7 is a sectional view taken on the line 7—7 of Fig. 6 and Figs. 8 and 9 are perspective and vertical sectional views respectively of modifications of the brush material supporting elements.

In Figs. 6 and 7 I have shown a modification of my brush wherein an intermediate plate 20 is interposed between the heads 1 and 14 and the tufts are applied to alternate posts, the tufts between the head 1 105 and plate 20 being alternated with respect to those between the said plate and the head 14. This construction is particularly well suited for the manufacture of brushes of great width, although alternation of the 110

tufts is not essential. Furthermore, while I have shown in Fig. 7 a brush having only one intermediate plate, it will be evident that any number of such intermediate plates 5 may be employed; and the movable head of a brush of this type may be forced toward the fixed head to compress the brush knots and may be locked to the upper ends of the posts by a simple stroke of the die 15, in the 10 same manner as described hereinbefore for the brush shown in Figs. 1 to 6.

The heads 1 and 14 are provided with registering openings in the centers thereof, which openings are for the purpose of enabling 15 the brush to be mounted upon an arbor or other operating support, as is customary.

For the purpose of enabling the upper 20 ends of the posts to support their extensions and to be expanded into heads for locking the head 14 thereto, at least the upper end of each of said posts is tubular, as shown; and the term "tubular" as employed in the 25 claims is intended to embrace posts which are tubular in part as well as tubular throughout their entire length.

Having thus described my invention, what I claim is:—

1. The process of making a brush which 30 comprises providing a head with tubular posts, inserting extensions into the ends of such posts which are remote from such head, applying tuft material to said posts and extensions, applying to such extensions a head 35 having openings for the reception of such extensions and for the ends of the posts in which the said extensions are mounted, forcing the second mentioned head along such extensions and onto the ends of the posts, 40 thereby compressing the tuft material and stripping it from the extensions, and expanding such post ends, thereby to lock the same into engagement with the metal surrounding the openings in the second head.

45 2. The process of making a brush which comprises providing a head with tubular posts, inserting extensions into the ends of such posts which are remote from such head, applying tuft material to said posts and extensions, applying to such extensions a head having openings for the reception of such 50 extensions and for the ends of the posts in which the said extensions are mounted, forcing the second mentioned head along such extensions and onto the ends of the posts, 55 thereby compressing the tuft material and stripping it from the extensions, and operating said extensions thereby to expand the ends of the posts in which they are respectively mounted into locking engagement 60 with the second mentioned head.

65 3. The process of making a brush which comprises providing a head with posts having extensions, applying tuft material to the

posts and extensions, applying to the extensions a head complementary to the first mentioned head and having openings for such extensions and for the ends of the posts carrying the same, forcing the second mentioned head along the extensions and onto the ends of the posts, thereby compressing the tuft material and stripping it from the extensions, and securing the second mentioned head to the said posts.

4. The process of making a brush which 75 comprises providing a head with posts, applying extensions to the ends of the posts which are remote from such head, applying tuft material to the posts and extensions, applying to the extensions a head complementary to the first mentioned head and having openings for such extensions and for the ends of the posts carrying the same, forcing the second mentioned head along the extensions and onto the ends of the posts, 80 thereby compressing the tuft material and stripping it from the extensions, and locking the second head to the said posts through movement of the said extensions toward the first mentioned head.

90 5. The process of making a brush which comprises providing a head with posts, applying removable extensions to the ends of such posts which are remote from such head, applying tuft material to said posts and extensions, applying to such extensions a head having openings for the reception of such extensions and for the ends of the posts carrying the same, forcing the second mentioned head along such extensions and onto 95 such ends of the posts, thereby compressing the tuft material and stripping it from the extensions, and securing the second mentioned head to the ends of the said posts which are remote from the first mentioned head.

100 6. The process of making a brush which comprises providing a head with posts having removable extensions, applying tuft material to the posts and extensions, compressing the tuft material toward said head and stripping it from the extensions, and securing a second head to the said posts and in operative engagement with such compressed tuft material.

110 7. The process of making a brush which comprises providing a head with posts having removable extensions, applying tuft material to the posts and extensions, compressing the tuft material toward said head and 120 stripping it from the extensions, and securing a head to the first mentioned head and in operative engagement with such compressed tuft material.

125 In testimony whereof, I hereunto affix my signature.

ARTHUR W. LAMP.
